Application December 10, 1953, Serial No. 397,293

17 Claims. (Cl. 188—69)

This invention relates generally to pumping apparatus for use in oil wells or the like and more particularly to novel means for preventing loss of fluid head when the pumping apparatus is stopped.

Oil well pumps of the reciprocating type are usually provided with a foot valve or check valve adjacent the intake of the pump in order to prevent loss of the fluid head of oil from the pump and production tubing both during operation of the pump and during a period when the pump is stopped for any reason. However, there are frequent occasions where the oil or other fluid being pumped contains objectionable quantities of abrasive material, such as sand, with the result that any conventional valve structure which may be provided at the intake end of the pumping apparatus is subject to severe erosion and consequently has a short life.

In the pumping apparatus of the present invention, the conventional foot valves or check valves are entirely eliminated so that the apparatus can readily handle abrasive material. Nevertheless, it is still desirable to make adequate provision for preventing loss of fluid head when the pump is stopped for any reason. Furthermore, it is frequently desirable to utilize a reversible pumping apparatus so that fluid can be pumped downwardly into the well for forcefully flushing the producing formation. Obviously, with such a reversible pumping apparatus the elimination of the conventional check or foot valve arrangement is necessary in order to permit the desired reversible operation.

Accordingly, a primary object of the invention is to provide novel means in a pumping apparatus for preventing loss of fluid head when the pump is stopped.

Another object of the invention is to provide a novel reversible pumping apparatus for use in oil wells or the like and including flow control means for preventing loss of fluid head.

A further object of the invention is to provide a novel combination of a reversible pumping apparatus and means for preventing loss of fluid head without the use of conventional valve structure.

Other objects and advantages of the invention will become apparent from the subsequent detailed description taken in conjunction with the accompanying drawings, wherein:

Fig. 1 is an elevational view on a reduced scale of a complete oil well pumping apparatus embodying the features of my invention and showing the apparatus in position in the well casing;

Fig. 2 is a fragmentary vertical sectional view on an enlarged scale of a portion of the apparatus illustrated in Fig. 1;

Fig. 3 is a fragmentary vertical sectional view on a still further enlarged scale showing a portion of the apparatus illustrated in Fig. 2 in one of its operating positions;

Fig. 4 is a view similar to Fig. 3 but showing the apparatus in a different operating position;

2

Fig. 5 is a transverse sectional view on a reduced scale taken along the line 5—5 of Fig. 3;

Fig. 6 is a fragmentary transverse sectional view looking upwardly along the line 6—6 of Fig. 3;

Fig. 7 is a fragmentary transverse sectional view looking downwardly along the line 7—7 of Fig. 3, and

Figs. 8 and 9 are diagrammatic side elevational views of a portion of the apparatus illustrating an operating principle of the invention.

10 Referring first to Fig. 1, the fragmentary lower portion of an oil well casing 11 is shown with the surrounding earth formation being indicated at 12. It will be understood that the casing 11 extends in the usual manner from the ground level to the bottom of the well 15 although neither of the extreme ends of the casing are illustrated in the drawing. The pumping apparatus embodying the features of my invention is shown in position in the well casing and comprises a plurality of sections connected in end-to-end relation for fluid flow therebetween.

20 At the top of the apparatus is a valve section A which includes a check valve and a drain valve. The check valve is normally not in use but can be put into operation in order to facilitate starting of the apparatus under 25 heavy load. The drain valve may be of the sleeve type for permitting oil to be drained from the tubing into the well casing when necessary in order to prevent the pulling of a "wet string." The function of the valve section A is not particularly related to the operation of 30 the remainder of the apparatus and the details thereof do not form any part of the present invention. Reference is made to my copending application Serial No. 319,995, filed November 12, 1952, now Patent No. 2,752,861, for a more complete disclosure of this portion 35 of the apparatus.

Below the section A of the pumping apparatus is a pressure balancer or equalizer section designated at B for regulating the pressure of the transformer oil in the motor compartment. Next below the section B is a section 40 designated at C which includes a brake and an actuating solenoid which are hereinafter described in detail since they comprise the principal feature of the present invention. A reversible motor section D, comprising in this instance a pair of induction motor units 13, is disposed below the section C and is connected to a reversible pump section F by means of a universal coupling section E. A cable 14 comprising the electrical conductors for supplying electrical energy to sections C and D is also provided and extends downwardly from the ground 45 level through the casing 11 and enters the apparatus at section B as shown.

50 Although the invention has broad utility, it is illustrated herein in connection with a reversible pumping apparatus so that in one direction of operation oil can 55 be pumped upwardly from the well and in the opposite direction of operation oil or other fluid can be forced downwardly into the well under pressure. Thus, during 60 production the reversible motor section D is operated so that the reversible pump section F draws oil from the bottom of the well casing and discharges the oil through suitable passageways provided in sections A to E for discharge through a tubing string 16 which is connected to a tank or other storage facilities at the ground level. When the producing formation or the intake to the apparatus becomes clogged or obstructed to an objectionable 65 degree, as indicated for example by a low volume of oil issuing from the well, the motor is reversed and the pump is thereby operated in the opposite direction so that oil or other suitable purging material is pumped downwardly 70 and is discharged from the pump under pressure. In order to insure that the oil or other pressurizing fluid is forcibly injected into the adjacent producing formation

at the bottom of the well, a suitable expandable packer section **G** is provided. In this instance, a packer **17** of the bottom hole type is shown connected at the inlet end of the pump section **F** but it will be understood that a side wall packer or any suitable packer of a type adapted to resist upward pressure may also be utilized. A fluid intake **18** in the form of a length of perforated or slotted pipe is shown in broken lines and it will be understood that this fluid intake is connected below the packer **17** or in place thereof in the event that a side wall packer is utilized.

In the embodiment shown in the drawing by way of illustration, the packer **17** is of a conventional type including an axially compressible rubber sleeve which is retracted as initially installed in the well casing. However, by means of a telescoping action, well known in the packer art, slideable sections of the pump casing are shifted after the apparatus is in place in the well and the rubber sleeve is compressed and bulged outwardly into tight-fitting sealed relation with the inside of the casing **11**. In this manner, it will be understood that the packer **17** effectively segregates the lower portion of the well so as to define a reservoir space between the packer and the bottom of the well. Thus, when oil or other purging fluid is pumped downwardly into the well under pressure, the reservoir space is sealed at its upper end by the packer **17** and the oil is therefore readily forced under high pressure into the obstructed producing formation or strata for purging and cleaning the same. At the same time, the pump intake **18** is also cleaned and flushed out.

As also seen in Fig. 1, the invention is illustrated in connection with a reversible positive displacement pump of the Moyno type. Thus, in section **F** of the apparatus there is shown an elongated female helical member **19** which constitutes the stator of the pump and an elongated male helical member **21** mounted within the female member and constituting the rotor of the pump. The outer member or stator **19** is provided with one helical thread more than the inner member or rotor, and the two members are so arranged and shaped that every thread of the rotor is constantly in contact with the stator in any transverse section through the pump. This relation of the rotor and stator is such that a plurality of closed spaces or cavities are defined between the two members because of the difference in the number of threads on each member. When the rotor is rotated relative to the stator, the cavities or spaces between the members are displaced in a longitudinal direction with the result that a fluid material can be axially transported between the two members to obtain the desired pumping effect. Reference is made to U.S. Patents Nos. 1,892,217 and 2,028,407 for a detailed consideration of the theory and operation of the progressing cavity or Moyno type pump.

Referring now to Figs. 2 to 9, the primary novel features of the invention will be described in connection with the details of the solenoid and brake section **C**. As previously mentioned, in the present invention the lower or inlet end of the apparatus is not provided with any special foot or check valve arrangement to prevent loss of fluid head from the system. The elimination of such conventional intake valve structure is desirable in order to facilitate reversible operation of the apparatus, as hereinbefore described, and also to permit the pumping apparatus to be utilized even where the oil or other fluid being pumped contains appreciable amounts of abrasive material such as sand which would have a detrimental erosive effect on ordinary valve structures. However, when the valve structure at the intake end of the pump is eliminated, it is still desirable to make some provision for preventing the loss of fluid head when the pump is stopped for any reason. For example, if the pump is stopped during a production period, it will be seen that the hydrostatic pressure of the head of oil in the production tubing **16** above the pump will tend to force oil downwardly through the pump causing the latter to

"motor" with consequent loss of fluid head. According to the present invention, I prevent such undesirable "monitoring" of the pump by utilizing a suitable brake which holds the pump rotor **21** in fixed position relative to the stator **19** whenever the motor and pump are stopped for any reason. Obviously, the very nature of the Moyno pump is such that leakage of oil or other fluid back into the well through the pump will be prevented as long as the pump rotor **21** is held against rotation.

As seen in Fig. 2, the upper end of the rotor shaft of the motor, designated at **22**, extends upwardly through a bearing **23** mounted in a partition or brake housing structure **24**. A cup-shaped rotatable member **26**, comprising one of a pair of complementary brake members, is keyed to the upper extremity of the rotor shaft **22**, the shaft extending upwardly through the base of the cup-shaped member **26** and being provided with a washer **27** and a lock nut **28** for further rigidly securing the brake member **26** on the rotor shaft **22** of the motor. Thus, the brake member **26** rotates with the shaft **22** but is held against axial movement. The upper annular edge of the cup-shaped brake member **26** is serrated or notched to provide a plurality of dogs or teeth **29** as hereinafter described in detail.

A complementary brake member is provided in the form of an inverted generally cup-shaped member **31** disposed in opposed coacting relation above the brake member **26**. The brake member **31** has a tubular extension **32** in which is slidably received an elongated actuating member **33** having an enlarged head portion **34** disposed within the cup-shaped member **31** for supporting and actuating the latter as hereinafter described in detail. As will also be described in greater detail hereinafter, the lower annular edge of the brake member **31** is likewise serrated or notched to provide a plurality of dogs or teeth **36** adapted to be engaged with the teeth **29** on the complementary brake member **26**.

The housing **24** extends upwardly to provide a generally tubular wall portion **37**, and a plurality of radial pins **38** project outwardly from the brake member **31** for coaction with the housing. The housing **24**—**37** is held against rotation by being secured by means of screws **35** to a solenoid housing **40** which is in turn rigidly held in the apparatus casing. As best seen in Figs. 3 to 5, the pins **38** have a threaded connection, as at **39**, in the wall of the cup-shaped brake element **31** and carry annular resilient cushions or shock absorbers **41** of rubber or the like, the rubber cushions being secured on the pins **38** between a pair of concentric supporting bands or rings **42** and **43**. As will be evident particularly from Fig. 5, the pins extend rigidly from the brake member **31** through elongated vertical slotted portions **44** provided in the tubular wall **37** of the fixed housing. Consequently, it will be readily understood that the brake member **31** is substantially held against rotary movement but can undergo a slight deflection in a rotary direction by reason of the resilient rings or cushions **41** interposed between the retaining pins **38** and the walls of the grooves or slots **44** provided in the housing **37**. Moreover, it will also be seen that by reason of the vertical elongation of the slots **44**, the uppermost brake member **31** can undergo limited vertical axial movement both in conjunction with and relative to the elongated actuating member **33** for effecting engagement and disengagement between the teeth or dogs **29** and **36** of the respective clutch members. Thus, upon upward movement of the member **33**, the uppermost brake member **31** will be lifted upwardly to effect release of the device. Upon downward movement or release of the actuating member **33**, the brake member **31** is free to move downwardly into braking engagement with the brake member **26**. A coil spring **46** is provided for normally urging the brake member **31** downwardly into engaged relation with the opposite brake member **26**, the spring **46** coacting between the upper end of the brake member **31** and a shoulder portion **47** on the housing **37**.

For effecting shifting movement of the upper brake member 31, a solenoid 48 is mounted above the brake mechanism in its housing 40 and includes an energizing winding as well as a shiftable plunger. A connector 49 having a swivel connection with the plunger of the solenoid is threadedly attached and locked, as at 51, to the upper end of the actuating member 33 for operating the latter. Although the circuit connections are not shown in the drawing, the energizing winding or coil of the solenoid 48 is preferably connected in circuit with the electric motor section D and a plurality of conductors 52 so that whenever the motor is in operation the solenoid 48 will be energized and the actuating member 33 will be held in its uppermost position with the brake member 31 thereby being lifted into disengaged position. However, if the current to the motor is interrupted for any reason so that the operation of the pump ceases, it will be seen that the brake member 31 will be immediately released by the solenoid 48 and the spring 46 will then force the brake member 31 into braking engagement with the lower brake member 26. With the rotor shaft 22 of the motor thus held against movement by the brake mechanism, it will be understood that the pump rotor 21 cannot rotate and consequently it is impossible for the fluid head above the pump to flow through the pump structure. In other words, the pump itself then serves as a valve and there is no opportunity for the fluid pressure exerted by the hydrostatic head to effect "motoring" of the pump with consequent drainage of the fluid to the bottom of the well.

In order to maintain a proper coaxial relationship between the upper and lower brake members 31 and 26, I also provide an annular bushing 53 (Figs. 3 and 4) which has a rigid press fit within the upper cup-shaped brake member 31. The bushing 53 is of sufficient axial length to extend downwardly within the lower cup-shaped brake member 26, and the lower end of the bushing 53 is formed with a guiding lip or bead 54 which extends circumferentially around the bushing in sliding engagement with the inner periphery of the brake member 26. Thus, at all times the necessary coaxial relationship between the brake members 31 and 26 is maintained so as to insure proper engagement and disengagement of the respective brake teeth.

As will be evident from the foregoing description, the guide bushing 53 provides a telescopic sliding relation between the respective cup-shaped brake members 31 and 26 so that axial shifting movement of the upper brake member 31 with its rigidly attached bushing 53 relative to the lower brake member 26 is in effect a piston and cylinder arrangement. As is usual in motors of this type, the motor section D contains a suitable fluid such as a transformer oil, and this oil is also present throughout the solenoid and brake section C and the pressure equalizing section B. Thus, the entire brake mechanism is surrounded or immersed in the transformer oil. Because of the telescopic or piston and cylinder operating relation between the respective brake members, as just described, it will be seen that the transformer oil which is confined between the cup-shaped brake members 31 and 26 exerts a damping or cushioning action in the manner of a dashpot so as to slow down the downward movement of the brake member 31 under the action of the spring 46. The displacement of the confined transformer oil during downward movement of the brake member 31 toward the brake member 26 is controlled, in this instance, by providing a predetermined clearance between the guide lip or bead 54 and inner periphery of the brake member 26. For this purpose, the lip or bead 54 is formed with a plurality of flats 56 (Figs. 3 and 7) so that the displaced fluid may be forced from between the brake members at the desired rate.

The dashpot or damping action during braking movement of the upper brake member is important for most satisfactory operation of the apparatus because of the fact that the brake is of the dog type. In other words,

during operation of the apparatus the rotor shaft 22 of the motor is rotating at a very high speed and the damping or dashpot action for delaying the engagement of the brake is necessary in order to permit the rotor shaft 22 to slow down after the current supply to the motor has been interrupted. If an attempt were made to engage the brake members during high speed rotation of the rotor shaft 22, it will be readily apparent that excessive shearing forces would be exerted on the brake teeth and also on the retaining pins 38. Consequently, the delayed braking action is a highly desirable feature of the invention.

Referring particularly to Figs. 3 and 4, the general operation of the brake mechanism will now be described. In Fig. 3 the device is shown in running position, i.e., with the motor and pump in operation. The solenoid 48 being energized by the same source of electrical energy which energizes the motor, it will be understood that the actuating member 33 is retained in its uppermost position with the upper brake member 31 being supported on the enlarged head 34 and thereby held in lifted or disengaged position.

In Fig. 4, the brake mechanism is shown in engaged position after the motor has been stopped. When the current supply to the motor and the solenoid 48 is interrupted, the actuating member 33 falls by gravity until the head portion 34 rests on the upper end extremity of the rotor shaft 22 thereby releasing the brake member 31. With the brake member 31 thus released, the spring 46 forces the brake member downwardly but the movement is damped or slowed by the dashpot action hereinbefore described due to the restricted displacement of fluid from between the brake members. In the meantime, of course, the rotation of the rotor shaft 22 with the brake member 26 mounted thereon has slowed down considerably, and finally the desired engagement between the brake teeth is accomplished. At the instant of braking engagement, any rotary force imparted to the brake member 31 is absorbed by reaction of the cushioned pins 38 against the walls of the slots 44. With the brake teeth in engagement as shown in Fig. 4, it will be understood that the radial retaining pins 38 hold the entire mechanism, including the pump rotor 21, against rotation.

When the current supply to the motor and solenoid 48 is again restored, the rotor shaft 22 tends to rotate and simultaneously the solenoid 48 lifts the actuating member 33 upwardly and the upper brake member 31 is ultimately lifted out of engagement with the lower brake member to permit free rotation of the latter. It will be understood that even when the brake members are engaged as in Fig. 4 there is a very slight clearance between the respective teeth 29 and 36. Consequently, it will be seen that if the motor is operating in a given direction, is then stopped so that the brake engages, and is subsequently started up again in the reverse direction, the slight edgewise clearance between the brake teeth will permit a very slight degree of reverse rotary movement of the lower brake member 26, and in this instant the upper brake member 31 can readily be retracted axially with minimum resistance. In other words, a reversal in the direction of operation of the pump during a start-up permits the clutch to be disengaged with a minimum load or frictional resistance between the brake teeth.

However, it will be also appreciated that if the pump is restarted in the same direction of rotation, the initial frictional resistance between the brake teeth is maintained and consequently the upper brake member must be retracted under maximum load. In order to overcome any tendency for the brake mechanism to stick when the pump is thus restarted in the same direction, I preferably employ a solenoid 48 of the heavy duty type sufficient to overcome the frictional resistance tending to hold

the brake members in engaged relation. In addition, it will be seen that the actuating member 33 has a sliding relationship in the tubular extension 32 of the upper brake member 31 and as a result there is a lost motion relation between the head portion 34 of the actuating member 33 and the underside or base of the brake member 31. Thus, in Fig. 4, when the solenoid 48 is actuated it will be seen that the actuating member 33 is lifted upwardly and gains considerable momentum during the time in which the head portion 34 travels from its position of rest on the end of the rotor shaft 22 into impacting engagement with the brake member 31. The delayed impact or hammer blow thus imparted to the brake member 31 assists materially in disengaging the brake member 31 under load and thereby overcomes any tendency toward sticking.

As seen in Figs. 3 and 4, the upper brake member 31 also has a pair of apertures or bores 58 which are normally closed by a pair of cap screws 59. These screws 59 may be removed when necessary to permit insertion of a pin or other tool in order to eject the press-fitted guide bushing 53 from the brake member 31 thereby facilitating repair or maintenance of the device. Also, in the event that it is desired to minimize the dashpot action between the brake members 31 and 26, it will be seen that the removal of one or both screws 59 will allow more rapid displacement of the confined oil during braking movement of the member 31 and thereby decrease the extent of damping action.

In the foregoing description it was pointed out that the dashpot or damping action as a result of the presence of transformer oil slows down the axial shifting movement of the upper brake member 31 so as to provide ample time for proper reduction in the speed of rotation of the rotor shaft 22 before the upper brake member 31 attempts to engage with the lower brake member 26. Because of the very slight clearance between the respective teeth of the brake members, the desired degree of register between the teeth for braking engagement requires that the rotor shaft 22 be almost entirely stopped. In order to insure this result, I have shown (Figs. 6-9) the teeth 36 on the upper brake member 31 with beveled or slanted corner edges, as at 57. These beveled corner edges function as cam surfaces so as to produce an upward rebound of the upper brake member 31 whenever the beveled edges 57 are engaged by the corresponding corner edges of the teeth 29 on the rotating lower brake member 26. Thus, in Fig. 8 the upper brake member 31 is shown in downwardly moving relation, as indicated by the arrow, and the lower brake member 26 is still rotating in the direction indicated by the arrow. In the situation shown in the drawing, the teeth 36 on the upper brake member 31 are descending in non-registered relation with respect to the spaces between the teeth 29 on the lower brake member 26. Consequently, as seen in Fig. 9, the right hand corner edges of the teeth 29 on the rotating lower brake member 26 strike an impacting blow against the left hand beveled corner edges 57 of the teeth 36 on the upper brake member 31 whereupon the latter is caused to rebound upwardly. This rebounding impact between the respective teeth is repeated again and again until such time as the speed of rotation of the brake member 26 is reduced sufficiently so that the downwardly urged brake member 31 can enter into clutching engagement with the lower brake member 26 when the respective toothed portions thereof are in substantially exact register. Obviously, this same rebound effect will be realized during reverse operation of the apparatus but the rebounding impact will take place in this case between the left hand corners of the teeth 29 and the right hand beveled corner edges 57 of the teeth 36.

Although the invention has been described in connection with a certain specific structural embodiment thereof, it will be understood that various modifications and equivalent structures may be resorted to without depart-

ing from the scope of the invention as defined in the appended claims.

I claim:

1. Brake means for holding a member rotatably driven in one direction against rotation in the opposite direction when the driving means therefor is de-energized, comprising a stationary housing, a pair of coaxial brake members mounted in coacting relation within said housing and having cooperating teeth, one of said brake members being adapted to be operatively connected to the driven member for rotation therewith and the other of said brake members being non-rotatable but axially shiftable toward and away from the rotatable brake member for effecting engagement and disengagement therebetween, at least one retainer element extending outwardly from said shiftable brake member into coacting engagement with said housing for preventing rotation of said shiftable brake member about said axis, resilient cushioning means interposed between said retainer element and the coacting portion of said housing, spring means normally urging the shiftable brake member into braking engagement with the rotatable brake member, each of the teeth on one of said members having beveled corner edges for effecting axial rebound of said non-rotatable member during rotation of said rotatable member when said teeth are not in register for braking engagement, and means for retracting the shiftable brake member from said braking engagement in response to energization of the driving means for the driven member.
2. Brake means for holding a member rotatably driven in one direction against rotation in the opposite direction when the driving means therefor is de-energized, comprising a stationary housing having a plurality of vertical elongated slots, a pair of upper and lower brake members mounted coaxially in coacting relation within said housing, the lower of said brake members being adapted to be operatively connected to the driven member for rotation therewith and the upper of said brake members being non-rotatable but axially shiftable toward and away from the lower brake member for effecting engagement and disengagement therebetween, a plurality of retainer pins extending radially from said upper brake member and projecting into said vertical slots in said housing for preventing rotation of said upper brake member about said axis, the vertical elongation of said slots permitting up-and-down movement of said upper brake member, spring means normally urging the shiftable brake member into braking engagement with the rotatable brake member, and means for retracting the shiftable brake member from said braking engagement in response to energization of the driving means for the driven member.
3. Brake means for holding a member rotatably driven in one direction against rotation in the opposite direction when the driving means therefor is de-energized, comprising a stationary housing having a plurality of vertical elongated slots, a pair of upper and lower generally cup-shaped members mounted coaxially in opposed coacting relation and having their annular edges provided with cooperating teeth, said lower cup-shaped member being adapted to be operatively secured to the driven member for rotation therewith and said upper cup-shaped member being held against substantial rotation and being shiftably mounted for axial up-and-down movement for effecting engagement and disengagement between the respective teeth, a plurality of retainer pins extending radially from said upper cup-shaped member and projecting into said slots in said housing for preventing rotation of said upper cup-shaped member, the vertical elongation of said slots permitting up-and-down shifting movement of said upper member, resilient cushioning elements interposed between said pins and the sides of said slots, spring means coacting between said housing and said upper cup-shaped member for normally urging the latter downwardly into braking engagement with the lower

cup-shaped member, and means for retracting said upper cup-shaped member upwardly and out of said braking engagement in response to energization of the driving means for the driven member.

4. Brake means for holding a member rotatably driven in one direction against rotation in the opposite direction when the driving means therefor is deenergized, comprising a pair of upper and lower generally cup-shaped members coaxially mounted in opposed coacting relation and having their annular edges provided with cooperating teeth, said lower cup-shaped member being adapted to be operatively secured to the driven member for rotation therewith and said upper cup-shaped member being held against substantial rotation and being shiftably mounted for axial up-and-down movement for effecting engagement and disengagement between the respective teeth, a guide bushing rigidly mounted in one of said cup-shaped members and extending coaxially into the other of said cup-shaped members for maintaining coaxial relationship between said members, spring means coacting with said upper cup-shaped member for normally urging the latter downwardly into braking engagement with the lower cup-shaped member, means operable in response to engaging movement of said member for retarding meshing engagement until rotation of said rotatable member has substantially stopped, and means for retracting said upper cup-shaped member upwardly and out of said braking engagement in response to energization of the driving means for the driven member.

5. Brake means for holding a member rotatably driven in one direction against rotation in the opposite direction when the driving means therefor is deenergized, comprising a pair of coacting brake members having cooperating teeth, one of said members being adapted to be operatively connected to the driven member for rotation therewith and the other of said members being held against substantial rotation, one of said brake members also being shiftable into and out of braking engagement with the other of said brake members, means normally urging the shiftable brake member into braking engagement with the opposite brake member, releasing means for disengaging the shiftable brake member in response to energization of the driving means for the driven member, and means operable in response to engaging movement of said shiftable member for retarding the movement of said shiftable brake member into meshing engagement until rotation of the rotatable brake member has substantially stopped.

6. Brake means for holding a member rotatably driven in one direction against rotation in the opposite direction when the driving means therefor is deenergized, comprising a pair of brake members, one of said brake members being adapted to be operatively connected to the driven member for rotation therewith and the other of said brake members being held against substantial rotation, housing means for maintaining a fluid around and between said brake members, actuating means for effecting relative movement between the brake members for engaging and disengaging said brake members, and means providing a telescopic sliding piston and cylinder arrangement including a restricted passage for by-passing said fluid and operable upon said relative movement to displace the fluid between said brake members and thereby damps and retards the relative movement between said brake members during braking engagement thereof.

7. Brake means for holding a member rotatably driven in one direction against rotation in the opposite direction when the driving means therefor is deenergized, comprising a pair of coaxial toothed brake members, one of said brake members being adapted to be operatively connected to the driven member for rotation therewith and the other of said brake members being non-rotatable but axially shiftable toward and away from said one brake member for effecting engagement and disengagement of the toothed portions of said brake

members, housing means for maintaining fluid around and between said brake members, spring means normally urging said other brake member into braking engagement with said one brake member, and means for retracting said other brake member to effect disengagement in response to energization of the driving means for the driven member, said brake members having cooperating piston and cylinder portions thereof in telescopic sliding relation and including a restricted passage for by-passing the fluid, said portions displacing the fluid between said brake members through said passage upon the movement of said other brake member toward said one brake member, thereby damping and retarding said braking movement.

8. Brake means for holding a member rotatably driven in one direction against rotation in the opposite direction when the driving means therefor is deenergized, comprising a pair of upper and lower generally cup-shaped members mounted in opposed coacting relation and having their annular edges provided with cooperating teeth, said lower cup-shaped member being adapted to be operatively secured to the driven member for rotation therewith and said upper cup-shaped member being held against substantial rotation and being shiftably mounted for axial up-and-down movement for effecting engagement and disengagement between the respective teeth, spring means coacting with said upper cup-shaped member for normally urging the latter downwardly into braking engagement with the lower cup-shaped member, means for retracting said upper cup-shaped member upwardly and out of said braking engagement in response to energization of the driving means for the driven member, housing means for maintaining fluid around and between said cup-shaped members, and means cooperating with said cup-shaped members to provide a telescopic sliding piston and cylinder relation therebetween including a restricted passage for by-passing the fluid, whereby the fluid confined between said cup-shaped members exerts a dashpot or damping effect for slowing the movement of said upper cup-shaped member into braking engagement with said lower cup-shaped member.

9. Brake means for holding a member rotatably driven in one direction against rotation in the opposite direction when the driving means therefor is deenergized, comprising a pair of upper and lower generally cup-shaped members mounted in opposed coacting relation and having their annular edges provided with cooperating teeth, said lower cup-shaped member being adapted to be operatively secured to the driven member for rotation therewith and said upper cup-shaped member being held against substantial rotation and being shiftably mounted for axial up-and-down movement for effecting engagement and disengagement between the respective teeth, spring means coacting with said upper cup-shaped member for normally urging the latter downwardly into braking engagement with the lower cup-shaped member, means for retracting said upper cup-shaped member upwardly and out of said braking engagement in response to energization of the driving means for the driven member, housing means for maintaining fluid around and between said cup-shaped members, and a guide bushing mounted in said upper cup-shaped member and extending coaxially into said lower cup-shaped member to provide a telescopic sliding piston and cylinder relation between said members and including a restricted passage for by-passing the fluid, whereby the fluid confined between said cup-shaped members exerts a dashpot or damping effect for slowing the movement of said upper cup-shaped member into braking engagement with said lower cup-shaped member.

10. The structure of claim 9 further characterized in that said restricted passage is a predetermined clearance provided between said bushing and said lower cup-shaped member for controlling the displacement of fluid from

between said cup-shaped members during braking movement.

11. Brake means for holding a member rotatably driven in one direction against rotation in the opposite direction when the driving means therefor is deenergized, comprising a pair of upper and lower generally cup-shaped members mounted in opposed coaxing relation and having their annular edges provided with cooperating teeth, said lower cup-shaped member being adapted to be operatively secured to the driven member for rotation therewith and said upper cup-shaped member being held against substantial rotation and being shiftably mounted for axial up-and-down movement for effecting engagement and disengagement between the respective teeth, spring means coaxing with said upper cup-shaped member for normally urging the latter downwardly into braking engagement with the lower cup-shaped member, means for retracting said upper cup-shaped member upwardly and out of said braking engagement in response to energization of the driving means for the driven member, housing means for maintaining a fluid around and between said cup-shaped members, an annular bushing rigidly held in said upper cup-shaped member and extending coaxially into said lower cup-shaped member, and a circumferential guide lip on said bushing slidably engaging the inner periphery of said lower cup-shaped member for providing a telescopic relation between said cup-shaped members, said lip having a plurality of flats thereby providing a predetermined clearance between said bushing and said lower cup-shaped member whereby to control the displacement of fluid from between said cup-shaped members through said clearance during braking movement, the fluid confined between said cup-shaped members exerting a dashpot or damping effect for slowing the movement of said upper cup-shaped member into braking engagement with said lower cup-shaped member.

12. Brake means for holding a member rotatably driven in one direction against rotation in the opposite direction when the driving means therefor is deenergized, comprising a pair of coaxing brake members having cooperating teeth, one of which is adapted to be operatively connected to the driven member for rotation therewith and the other of which is held against substantial rotation, one of said brake members also being shiftable into and out of braking engagement with the other of said brake members, means normally urging the shiftable brake member into braking engagement with the opposite brake member, and releasing means for disengaging the shiftable brake member in response to energization of the driving means for the driven member, said releasing means comprising an actuating member having a sliding lost motion connection with the shiftable brake member and including an operating portion adapted to engage the shiftable brake member with a delayed impact following said energization whereby to overcome any tendency of the brake members to resist disengagement under load.

13. Brake means for holding a member rotatably driven in one direction against rotation in the opposite direction when the driving means therefor is deenergized, comprising a pair of upper and lower generally cup-shaped members mounted in opposed coaxing relation and having their annular edges provided with cooperating teeth, said lower cup-shaped member being adapted to be operatively secured to the driven member for rotation therewith, an elongated actuating member having said upper cup-shaped member slidably mounted thereon and including an enlarged portion at its lower end for engaging and lifting said upper cup-shaped member, means holding said upper cup-shaped member against substantial rotation, spring means coaxing with said upper cup-shaped member for normally urging the latter downwardly into braking engagement with the lower cup-shaped member, and means for axially retracting said actuating member upwardly whereby to lift said upper cup-shaped member

10 out of said braking engagement in response to energization of the driving means for the driven member, said actuating member being slidably downwardly relative to said upper cup-shaped member when said cup-shaped members are in braking engagement to position said enlarged portion in spaced relation below the upper cup-shaped member so that upon retracting of said actuating member the enlarged portion thereof engages the upper cup-shaped member with a delayed impact for overcoming any tendency toward sticking.

15 14. The structure of claim 13 further characterized in that said lower cup-shaped member is affixed to a shaft member extending upwardly through the base thereof, said shaft member being operatively connectible with the driven member, and said enlarged portion at the lower end of said actuating member is operatively supported on the upper end of said shaft member in spaced relation below the base portion of the upper cup-shaped member during braking engagement of said cup-shaped members.

20 15. Brake means for holding a member rotatably driven in one direction against rotation in the opposite direction when the driving means therefor is deenergized, comprising a pair of toothed brake members mounted in opposed coaxing relation, one of said brake members being adapted to be operatively connected to the driven member for rotation therewith and the other of said brake members being non-rotatable but shiftable toward and away from the rotatable brake member for effecting engagement and disengagement between the toothed portions of the respective brake members, spring means normally urging the shiftable brake member into braking engagement with the rotatable brake member, and means for retracting the shiftable brake member from said braking engagement in response to energization of the driving means for the driven member, each of the teeth on one of said toothed brake members having beveled corner edges for causing axial rebound of the non-rotatable brake member during attempted engagement of the brake members while the rotatable brake member is still rotating and the toothed portions of the brake members are not in register for braking engagement.

25 16. Brake means for holding a member rotatably driven in one direction against rotation in the opposite direction when the driving means therefor is deenergized, comprising a pair of toothed brake members mounted in opposed coaxing relation, one of said brake members being adapted to be operatively connected to the driven member for rotation therewith and the other of said brake members being non-rotatable but shiftable toward and away from the rotatable brake member for effecting engagement and disengagement between the toothed portions of the respective brake members, spring means normally urging the shiftable brake member into braking engagement with the rotatable brake member, and means for retracting the shiftable brake member from said braking engagement in response to energization of the driving means for the driven member, each of the teeth on said non-rotatable brake member having beveled corner edges so as to cause axial rebound of the non-rotatable brake member upon impact of said beveled edges against the corners of the teeth on the rotatable brake member during attempted engagement of the brake members while the rotatable brake member is still rotating and the toothed portions of the brake members are not in register for braking engagement.

30 17. Brake means for holding a member rotatably driven in one direction against rotation in the opposite direction when the driving means therefor is deenergized, comprising a pair of upper and lower generally cup-shaped members mounted in opposed coaxing relation and having their annular edges provided with cooperating teeth, said lower cup-shaped member being adapted to be operatively secured to the driven member for ro-

tation therewith and said upper cup-shaped member being held against substantial rotation and being shiftably mounted for axial up-and-down movement for effecting engagement and disengagement between the respective teeth, spring means coacting with said upper cup-shaped member for normally urging the latter downwardly into braking engagement with the lower cup-shaped member, and means for retracting said upper cup-shaped member upwardly and out of said braking engagement in response to energization of the driving means for the driven member, each of the teeth on said upper cup-shaped member having beveled leading and trailing corner edges so as to cause axial rebound of said upper cup-shaped member upon impact of said bevel edges against the corners of the teeth on said lower cup-shaped member during attempted engagement of the cup-shaped members while the lower cup-shaped member is still

5

rotating and the teeth of the respective cup-shaped members are not in register for braking engagement.
